ATTORNEY.

UNITED STATES PATENT OFFICE

ELMER E. FREY, OF LOS ANGELES, CALIFORNIA

CAMPING BED

Application filed October 4, 1927. Serial No. 223,963.

This invention relates to camping beds and the principal object is to provide an improved structure which is readily capable of being extended and collapsed, at will, for rendering the bed operative and inoperative, respectively.

A more particular object is to provide a collapsible bed embodying a fabricated wire mattress, a collapsible frame for holding the mattress in tension when the bed is in use, and means for adjustable tensioning of the mattress to meet varying conditions of use.

I am well aware that camping beds embodying collapsible frames and tension mattresses have been extensively used and are old in the art, but I have provided and will hereafter describe an improved type of frame particularly adapted to support the mattress in tension, together with means for readily adjusting the tension of said mattress.

In the practice of my invention I have eliminated all superfluous parts and connections and have sought to provide a simplified structure which, when extended for use with the mattress in tension, will provide a rigid frame capable of sustaining substantially heavy weights on the bed without damage thereto.

Other objects may appear as the description progresses.

I have shown in the accompanying drawings a preferred embodiment of my invention, subject to modification within the scope of the appended claims, without departing from the spirit thereof.

In said drawings:

Fig. 1 is a perspective view of my improved camping bed assembled and extended for use.

Fig. 2 is a perspective view of the bed frame partially collapsed with the mattress removed therefrom.

Fig. 3 is a perspective view of the bed frame completely collapsed and arranged in a compact unit.

Fig. 4 is a fragmentary perspective view of one corner of the bed frame showing the

details of structure and connections between the several parts.

Fig. 5 is a perspective view of the mattress folded into a compact package.

Briefly described my improved bed includes a fabricated wire spring mattress M of well known form, having end rails E, E secured thereto, legs L, L etc. at the corners, side rails R and R' etc. connecting the legs longitudinally and suitable cross braces as at B and B' and b and b'. The legs and side rails are preferably formed of channeled iron, as clearly illustrated in the drawings, in order to afford maximum rigidity and strength. The channels of the legs are turned inwardly while the channels of the side rails are turned downwardly.

Each of the side rails is composed of a pair of channeled sections R and R' which are pivoted together at a point R' inwardly of the inner end of the sections R. The sections R' may be of smaller cross sectional dimensions than the rails R so that the inner ends of the smaller rails will telescope into the channels of the larger rails R. The ends r on both of the sections R and R' are bifurcated and the webs of the sections R and R' are cut away so that the furcations at the ends of the rail sections overlie the opposite sides of the legs L. The bifurcated ends of rails are pivotally connected with the legs L by means of bolts or rivets r'. The outer ends of the furcations r are preferably bent inwardly so as to slightly overlie the outer web portions of the legs, as shown in Fig. 4. Thus, when the legs are swung on the rails R and R' the furcations r will spring outwardly so that the inwardly bent edges thereof will frictionally engage the sides of the legs when the legs are positioned vertically with respect to the side rails, as shown in Fig. 4. The inwardly bent ends of the furcations r will serve to hold the legs temporarily in the position shown while the mattress M is being positioned thereon.

The side rail sections R and R' are provided with tensioning devices for the mattress M, each of which devices includes a pair of members D and D'. The member

D is of J shape with the bent portion thereof overlying the rail sections R and R' and pivotally connected therewith by means of bolts or rivets d. Member D is provided with a downwardly directed arm d1 which may have a lug d2 formed on the lower end thereof by means of which said arm may be raised and lowered. The member D' is of a channelled cross section and is pivoted to the upper bent portion of the member D on a bolt or rivet d'. Member D' has its opposite flanges gradually decreasing in width from its lower end to the upper end d3 thereof, and said upper end is adapted to frictionally engage one of a series of notches d4 which are formed on the inner edges of the legs L near the upper ends of the legs. When the mattress is in tension the heels d6 of the members D' will frictionally engage the upper sides of the rail sections R and R' while the webs of said members will engage the bent portions d5 of the members D.

The legs L are provided with tongues E1 which are bent outwardly from the webs of the legs and are adapted to engage apertures e formed in the vertical flanges e' of the mattress rails E. The mattress M is attached to the horizontal flanges e1 of the rails E and when it is operatively positioned on the frame it will be held against lateral movement by means of the tongues E1 while the flanges e1 will rest upon the upper ends of the legs L, L etc. Said legs are transversely connected in pairs at the ends of the bed by means of diagonal braces B and B' which are pivotally connected at their upper ends, respectively, to the transversely spaced legs and are pivotally connected together centrally of the legs at points B1.

The long brace sections B and B' are provided at their lower ends with short sections b and b', respectively. The section b is pivotally connected at B2 to the lower end of the section B' at its inner end and is pivotally connected at B4 at its outer end to the lower portion of one of the pair of legs L. In a similar manner the sections B' are pivoted at their inner ends as at B5, with the lower ends of the sections B while the outer ends thereof are connected as at B6, with the lower portions of the opposite legs L.

Thus, as shown in Fig. 1, the toggle joints between the two pairs of legs may be broken in order that the frame may be collapsed, and the opposite legs L, L may be moved into substantially abutting positions, as shown in Fig. 3. In this connection it will be noted that the rail sections R', as shown in Fig. 2, swing in a clock-wise direction and fold into the channels of the sections R. Also the legs L fold inwardly into the channels of the sections R and R'. The members D' of the tensioning units fold

downwardly against the webs of the said rails while the members D of said units are swung upwardly into substantial parallelism with the members D'.

When the bed is extended for use, with the mattress M in tension thereon, the members D' serve as angular braces for adjustably connecting the side rails and the legs.

In such case the tension of the mattress serves to pull the upper portions of the legs inwardly, thus causing a thrust of the braces D' downwardly at angles against the rails R and R'. The overlapping arrangement of the sections of the side rails causes the inner ends of the sections R to bear downwardly against the inner ends of the sections R'. The members D' are supported in position, when the mattress is in tension, by the movement of the members D downwardly so that the fulcrums d' will be below a line cutting the axes of the pivots d, and the upper ends d3 of each of the tensioning units. The tension of the mattress will exert pressure downwardly on the members D to prevent the accidental breaking of the toggle joints between the members D and D'.

In operation, when the bed frame and mattress are collapsed into compact bundles or packages, as shown in Figs. 3 and 5, respectively, the frame is extended, first by swinging the sections R' of the side rails outwardly into longitudinal alignment with the sections R, whereupon the two side rails may be drawn apart so as to move the end braces B—b' and B'—b into longitudinal alignment, for properly spacing the pairs of legs L, L at the ends of the bed frame, as shown in Fig. 1.

Thereafter, or before, as may be desired, the legs L may be swung into substantially right-angular positions with respect to the sections R and R' on the side rail, in which positions the legs will be temporarily held within the bifurcated end portions r of the side rails. The tensioning units may then be operated for connecting the upper ends of the members D' with one of the notches d4 in each of the legs, the members D being swung downwardly, as shown in Fig. 4, for maintaining such connections.

The mattress M, is then positioned on the upper ends of the legs L while the end rails E, E are pulled outwardly over the ends of the legs and the tongues E1 are forced into the apertures e. Usually the mattress is attached to the legs, and subsequently the tensioning units may be operated for engaging the portions d3 of said units with selected notches in the legs L for suitably tensioning the mattress.

What I claim is:

1. A folding bed comprising side rails, legs pivoted at points intermediate their ends to the side rails, means on the upper ends of the legs for supporting a mattress,

5 levers having U shaped attaching portions pivoted to and inwardly of the ends of the side rails, channeled arms eccentrically pivoted to said levers, cooperating means on the upper ends of said legs and said arms whereby the same may be adjustably engaged, said levers being operable for moving said arms in opposite directions over dead center position for supporting said arms in 10 locked and unlocked position, the lower ends of said arms abutting said side rails when the arms and legs are in locked position.

15 2. A folding bed comprising side rails, legs pivoted at points intermediate their ends to said side rails, means thereon for supporting a mattress in position for use, and tensioning devices for connecting said legs and said side rails for holding said mattress in tension, said devices including levers 20 pivoted for movement in vertical planes on and inwardly of the ends of the side rails, toggle arms pivoted to and at points spaced from the axes of said levers, cooperating means on the upper portions of said legs and said arms, whereby said legs and said arms may be adjustably engaged, said levers being operable for moving said arms over dead center position for adjustably tensioning said mattress, the lower ends of said arms 25 abutting said rails when locked in tensioning position.

30 3. A folding bed including a pair of side rails, legs pivoted at points intermediate their ends to the ends of said side rails, means on the upper ends of said legs for supporting a mattress in position for use, and toggle means pivotally attached to and inwardly of the ends of said side rails for holding said mattress in tension, said means 35 including sets of arms and levers movable in vertical planes, the lever of each set being pivoted to a side rail and the arm of each set being eccentrically connected with the associate lever, cooperating means on the 40 upper ends of said legs and said arms whereby the same may be adjustably engaged, said tensioning devices being operable for moving the axis of the arms over dead center of the levers in a tensioning operation, 45 the lower ends of said arms abutting said rails when the arms are in locked positions.

50 4. A folding bed comprising side rails, legs pivotally attached at points intermediate their ends to said side rails, means on 55 said legs for supporting a mattress, tensioning levers having channeled attaching portions overlying opposite sides of and pivotally attached to the side rails at points inwardly of the ends of the rails, channeled 60 arms overlying the rails and pivotally attached to and within the channels of the tensioning levers at points spaced from the axes of the levers, and cooperating means formed on the upper ends of the legs and 65 the arms for adjustably engaging the arms

and legs for holding a mattress in tension when the free ends of said levers are moved downwardly, and the axes of the arms are moved over dead center positions, the lower ends of said arms abutting said rails when 70 the arms are in locked positions.
